UNITED STATES PATENT OFFICE.

CHARLES R. WEAVER AND ANTHONY G. FLECK, OF NEW YORK, N. Y., ASSIGNEES TO
PNEUMATIC CONCRETE MACHINERY COMPANY, OF NEW YORK, N. Y., A CORPORATION
OF NEW JERSEY.

PNEUMATIC CONVEYER.

1,360,160.

Specification of Letters Patent. Patented Nov. 23, 1920.

Application filed November 27, 1917, Serial No. 204,227. Renewed October 14, 1920. Serial No. 417,024.

To all whom it may concern:

Be it known that we, CHARLES R. WEAVER and ANTHONY G. FLECK, citizens of the United States, and residents of New York, 5 in the county of New York and State of New York, have invented new and useful Improvements in Pneumatic Conveyers, of which the following is a specification.

This invention relates to pneumatic conveyers adapted to be used particularly in the conveying of concrete, although not restricted to such use.

An important object of the invention is to provide in a device of the above mentioned 15 character a means whereby the momentum of a bulk of concrete may be materially decreased immediately prior to the discharging of the same.

Another object of the invention is to provide in a device of the above mentioned character a means whereby the momentum of a bulk of concrete may be maintained at a predetermined constant immediately prior to the discharging of the same.

25 A further object of the invention is to provide in a device of the character described a means whereby concrete may be deposited at any desired point along the course of travel of the same.

30 Other objects and advantages of the invention will be apparent during the course of the following description.

In the accompanying drawings, forming a part of this specification and in which like 35 numerals are employed to designate like parts throughout the same,

Figure 1 is a side elevation of the device embodying our invention,

Fig. 2 is a central vertical sectional view 40 of a relief valve,

Fig. 3 is a longitudinal sectional view of a sleeve valve, showing the same in a closed position,

Fig. 4 is a longitudinal sectional view of 45 a sleeve valve, showing the same in an open position,

Fig. 5 is a transverse sectional view of Fig. 3 taken on the line 5—5,

Fig. 6 is a transverse sectional view of 50 Fig. 4 taken on the line 6—6,

Fig. 7 is a longitudinal sectional view of a sleeve valve associated with a discharge pipe showing an abutment positioned and secured therein, and,

55 Fig. 8 is a longitudinal sectional view of a portion of a discharge pipe.

In the drawings, wherein for the purpose of illustration is shown a preferred form of our invention, the numeral 10 indicates a hopper supported by any suitable means of 60 support. In this particular instance we have shown the same as being supported by a table or platform 11. Immediately below the hopper 10 there is suspended a second hopper indicated by the numeral 12 which 65 is adapted to receive therein from the hopper 10 a quantity of stone, sand, cement and water which is designed to be mixed by the self rotating effect imparted upon the same in its course of travel from the hopper 10 70 into the hopper 12. A discharge receptacle 13 is disposed directly beneath the hopper 12 and is adapted to receive therein concrete from the hopper 12, which is directed into the receptacle 13 by means of a collector 75 14 disposed upon the upper end thereof as shown. This discharge receptacle is provided interiorly thereof, at its upper end, with the conventional type of valve not shown, adapted to close the opening leading 80 therein through which the concrete is directed in its course of travel from the hopper 12 as hereinbefore described. The discharge receptacle 13 is provided also with the conventional form of fluid pressure supply 85 means which, in this instance, comprises a pipe 13' communicating a suitable source of fluid pressure with the interior of the receptacle 13. To the pipe 13' there is connected a second pipe 14' adapted to inject 90 fluid pressure into a discharge pipe 15 in the direction of travel of concrete which is adapted to be discharged from the receptacle 13 into and through the discharge pipe 15 under fluid pressure supplied to the interior of the discharge receptacle 13 by 95 means of the pipe 13' from a suitable source of pressure supply, not shown. A suitable valve 14'' is disposed within the pipe 14' and serves as a means for establishing or 100 severing communications between the pipes 13' and 14'.

This discharge receptacle 13 is preferably supported by means of supports 15' and has secured to the lower end thereof a 105 discharge pipe 15, comprising a plurality of sections 16. While we have shown a plurality of sections 16 which make up the discharge pipe 15, we wish it understood that this discharge pipe may be formed of one 110 continuous length if so desired. At desired intervals along the discharge pipe 15 there

is provided a plurality of openings 17 which are adapted to be opened or closed by means of sleeve-valves 18, rotatably mounted upon the discharge pipe 15, as clearly shown in 5 Figs. 3 and 4. These valves are provided with openings 19 similar to those provided by the discharge pipe 15 and indicated by the numeral 17. In order to prevent a longitudinal movement of the sleeve valves 18 10 in either direction upon the discharge pipe 15 there are provided annular collars 20, encircling the discharge pipe 15 adjacent the ends of the sleeve valves 18, which collars are adapted to be secured to the discharge 15 pipe in proximity to the ends of the sleeve valves by means of set screws or the like as shown at 21. The end section of the discharge pipe 15 is provided with a block or abutment 22, having a beveled face 23 as 20 shown. This block is retained within the end section by means of an internally screw-threaded cap 24, having screw-thread engagement with the discharge pipe 15 as shown at 25, and is adapted to be removed from the 25 end section and inserted into any one of the other sections through the openings provided therein, in which case it is held against displacement by means of one of the set-screws 21 which is run down through the 30 annular collar 20 and the wall of the discharge pipe 15 into engagement with the block, as shown in Fig. 7. This block serves as a means for deflecting the concrete in its course of travel through the discharge pipe 35 15 in the direction of the arrow shown in Figs. 7 and 8 when the same reaches the opening, within the discharge pipe, through which it is desired to spill or discharge the traveling concrete.

40 In order to deflect the concrete through any one of the desired openings it is necessary to impede the moving concrete in its course of travel. As a means for accomplishing this we have provided a plurality 45 of pressure releasing means which are disposed upon the discharge pipe 15 and spaced at desired intervals. Each of these pressure releasing means, comprises a flange 24', surrounding an opening 25' provided by the discharge pipe 15. To the flange 24' there is 50 secured a supporting frame 26 by means of internal and external screw-threads, as shown at 27, which are carried by the supporting frame 26 and flange 24, respectively.

55 The upper end of this supporting frame 26 carries therein a vertically adjustable sleeve 28, having external screw-threads adapted to engage internal screw-threads as shown at 29. In order to permit easy adjustment of 60 the sleeve 28 there is provided a hand wheel 30, secured to the upper end thereof, the sleeve 28 being provided with a lock nut 31 by which the same may be maintained in a desired locked position. We wish it understood however, that should it be desired this

lock nut may be dispensed with. A valve stem 32 is slidably mounted within the sleeve 28 and is provided at the lower end thereof with a valve 33 which is adapted to seat upon a valve seat 34 carried by the flange 24'. In 70 order to maintain the valve 33 normally in a closed position there is provided a compressible spring 35, carried by the valve stem 32, the upper end of which is adapted to engage the lower end of the sleeve 28, 75 while the lower end of the spring is adapted to engage the valve 33, as shown. To the upper end of the supporting frame 26 there is secured an arm 36 carrying thereon a graduated scale 37 with which a flange 38, 80 carried by the hand wheel 30 is adapted to register.

In use, the operation of the device is as follows: After a predetermined amount of concrete has been deposited within the receptacle 13 the same is discharged therefrom, by the conventional form of fluid pressure means, through the discharge pipe 15 and out of the opening provided by the end section, assuming, of course, that the 85 sleeve-valves 18 carried by the discharge pipe 15 are closed. Should it be desired to discharge the concrete from the discharge pipe 15 at any other point other than at the end of the discharge pipe a sleeve valve 18 90 is opened at the desired point and the block or abutment 22 is inserted therein as hereinbefore described. The point at which the concrete is desired to be discharged necessarily determines the tension to be 95 maintained within the coil spring 35 of the pressure releasing means. If it is desired to discharge the concrete through the opening provided at the end of the discharge pipe the flange 38 carried by the hand wheel 100 105 30 is brought into registration with a suitable graduation upon the arm 36 whereby a tension may be maintained within the spring 35 to allow the valve 33 to be raised as the concrete passes through the pipe 15 110 in order to permit a predetermined amount of fluid under pressure to be released from within the discharge pipe 15 thus impeding the concrete in its course of travel causing a gentle and even flow of the same through the 115 opening. Should it be desired to discharge the concrete through any one of the other openings the corresponding sleeve valve is 120 opened, the block inserted, and the spring 35 is set at the desired tension, as hereinbefore described, to release a sufficient amount of fluid pressure to effectuate a gentle and even flow of concrete through the selected opening in the same manner as described above when considering the discharge of concrete through the opening provided at the end of the discharge pipe.

It is to be understood that various changes in the shape, size, and arrangement of parts may be resorted to without departing from 130

the spirit of our invention or the scope of the subjoined claims.

Having thus described our invention, what we claim as new and desire to secure and protect by Letters Patent of the United States, is:

1. A device of the character described comprising a discharge pipe adapted to convey material under pressure, and means for 10 impeding the material in its course of travel through said pipe, said means consisting of a plurality of pressure actuated valves disposed upon said pipe.

2. A device of the character described 15 comprising a discharge pipe adapted to convey material therethrough, fluid pressure means for imparting momentum to the material, and means for decreasing the momentum of the material in its course of 20 travel through said pipe, the latter named means consisting of a plurality of pressure actuated valves disposed upon said pipe and means for varying the pressure point at which the valves will be actuated.

25 3. A device of the character described comprising a discharge pipe adapted to convey material therethrough, fluid pressure means for imparting momentum to the material, and fluid pressure releasing means 30 for relieving the pressure along the line of travel of material for impeding the movement thereof, the latter named means consisting of a plurality of pressure actuated valves disposed upon said pipe and means 35 for determining the pressure point at which said valves will be actuated.

4. A device of the character described 40 comprising a discharge pipe adapted to convey concrete therethrough, fluid pressure means for moving the concrete through said pipe, and a plurality of valves disposed upon said pipe and spaced apart to relieve the pressure whereby the movement of the concrete will be impeded, said valves being 45 actuated by the fluid pressure, and means for varying the pressure point at which said valves will be actuated.

5. A device of the character described 50 comprising a discharge pipe adapted to convey concrete therethrough, fluid pressure means for moving the concrete through said pipe, means for discharging the concrete from said pipe along the course of travel therethrough, and a plurality of spring 55 pressed valves disposed upon said pipe, said valves being operated by the fluid pressure, and means for varying the pressure point at which said valves will be operated.

6. In a pneumatic concrete conveyer for 60 conveying concrete under high pressure and at a high velocity, a discharge receptacle adapted for the reception of concrete, a discharge pipe connected with said discharge receptacle, pneumatic means for conveying

concrete through said discharge pipe from 65 said discharge receptacle, and means for releasing pneumatic pressure from said discharge pipe immediately prior to the discharge of concrete from the discharge end of said discharge pipe whereby the velocity 70 of the concrete will be materially decreased.

7. In a pneumatic concrete conveyer for conveying concrete under a high pressure and at a high velocity, a discharge receptacle adapted for the reception of concrete, 75 a discharge pipe connected to said discharge receptacle and provided with a pneumatic pressure relief vent in proximity to the discharge end of said discharge pipe, pneumatic means for conveying concrete through 80 said discharge pipe from said discharge receptacle under a high pneumatic pressure and at a high velocity, a relatively large proportion of the pneumatic pressure escaping through said pressure relief vent whereby the velocity of said concrete is materially reduced 85 immediately prior to its discharge from said discharge pipe.

8. In a pneumatic concrete conveyer for conveying concrete under a high pressure 90 and at a high velocity, a discharge receptacle adapted for the reception of concrete, a discharge pipe connected with said discharge receptacle, said discharge pipe being provided with a plurality of concrete discharge 95 openings, pneumatic means for conveying concrete from said discharge receptacle through said discharge pipe, the concrete being ejected from said discharge pipe through a selected opening, and means for releasing 100 a relatively large portion of the pneumatic pressure from said discharge pipe immediately prior to the discharge of concrete through a selected one of said openings whereby the velocity of the concrete will be 105 materially decreased.

9. In a pneumatic concrete conveyer for conveying concrete under a high pressure and at a high velocity, a discharge receptacle adapted for the reception of concrete, 110 a discharge pipe connected to said discharge receptacle and provided with a plurality of concrete discharge openings and a pneumatic pressure relief vent arranged in proximity to each of said concrete discharge 115 openings, pneumatic means for conveying concrete through said discharge pipe from said discharge receptacle under a high pneumatic pressure and at a high velocity, a relatively large proportion of the pneumatic 120 pressure escaping through one of said pressure relief vents whereby the velocity of said concrete is materially reduced immediately prior to its discharge through a given concrete discharge opening.

CHARLES R. WEAVER.
ANTHONY G. FLECK.
